UNITED STATES PATENT OFFICE

2,588,895

GAS BURNER WITH FLAME RETAINING PORTS

Ernest Edward Tavener, London, England, assignor to Keith Blackman Limited, London, England, a corporation of Great Britain

Application January 31, 1947, Serial No. 725,442
In Great Britain February 4, 1946

1 Claim. (Cl. 158—116)

1

This invention relates to improvements in gas burners, primarily though not exclusively for use in baking ovens, normally in the form of a long tube, that is, long in relation to its width, provided with a longitudinal slot or slots.

There has arisen a demand for a burner with a continuous, or substantially continuous flame, but capable of much greater heat output per unit of length than is practicable with burners of the usual types.

It is observed that when the mixture of gas and air issuing from a burner exceeds a certain velocity, it will not remain alight, the flame "lifting off" from the burner opening. If, however, another flame is held adjacent to the issuing mixture, the latter will burn satisfactorily at very high velocities. This ignition flame, so termed to distinguish it from the main or high velocity flame, can be fed from the mixture passing to the main flame, in which case the velocity of the mixture supplied to the ignition flame must be considerably reduced before it reaches its combustion point. One simple course is to use a restriction orifice in the port leading from the mixture supply to the point of combustion.

For many years, use has been made of a low velocity ignition flame surrounding a main high velocity flame. This ignition flame has usually been fed through a number of small holes, each with a restricted supply, disposed around the main orifice. In other cases an annular ignition flame has been used.

For the present purpose there is required, in contrast, a substantially continuous main flame, long in relation to its width.

A burner according to the invention presents a main slot (or slots) for the main flame, bordered along the length thereof, preferably on each side, by a supplementary slot for an ignition flame.

For example, a main central slot may be provided by two strips, separated by a spacer, to give the required width of slot. On each side of this assembly is placed a spacer so formed as to reduce the combustible mixture to a low velocity at the point of combustion. Flanking these spacers are further strips, the whole assembly comprising in this particular case seven elements, of which three are spacers.

The strip and spacer assembly may be fitted into a housing suitable for conveying combustible mixture and delivering it to the entrant side of the slots. This housing may conveniently be made from tubing, slotted to receive the strip assembly, and fitted with cross bolts to prevent

2

distortion of the housing under the influence of heat. The mixture may be delivered to one end of the housing which may contain a further apertured tube for rationing the mixture longitudinally of the burner to provide even or uneven heating, as required.

A gas burner according to the invention is illustrated in the accompanying drawings in which Fig. 1 is a perspective view and Fig. 2 a cross section of the strip and spacer assembly constituting the burner proper, and Figs. 3 and 4 are a longitudinal section and a cross section, respectively, showing the burner fitted into a housing.

15 Referring to the drawings, the burner shown presents a central slot 10 for a main flame, bordered along the length thereof on each side by a supplementary slot 11 for an ignition flame. The central slot 10 is provided by two strips 12, separated by a spacer 13, to give the required width of opening. On each side of this assembly is placed a spacer 14 so formed as to reduce the combustible mixture for the ignition flame to a low velocity at the point of combustion. Flanking these spacers 14 are outer strips 15. The strip and spacer assembly shown thus comprises seven elements, of which three are spacers.

The assembly is fitted into a housing 16 suitable for conveying a combustible mixture, and delivering it to the entrant side of the slots 10, 11. The housing 16 shown is made from tubing, slotted at 17 to receive the strip assembly, and fitted with cross bolts 18 to prevent distortion of the tube under the influence of heat. The mixture enters 30 one end of the tube at 19. 20 denotes a perforated rationing tube fitted within the housing 16 and serving to ration the mixture longitudinally of the burner to provide even or uneven heating, as required. Heat distribution along the length 35 of the burner may be further regulated by adjustment of a conical valve 21 co-operating with an orifice 22 in a partition 23 fitted into the inlet end of the housing 16.

The strips 12, 15 may be held together by rivets, 40 screws, welding or other means. 24 denotes straps for retaining the strip and spacer assembly in position in the housing 16. For convenience of manufacture, the spacers 13, 14 are preferably continuous, but serrated, the serrations being formed to permit the passage of mixture between the strips forming the boundaries of the burner outlets 10, 11. In the ignition spacers 14 the openings are each shorter at the entrant side than at the discharge point, where- 45 by the velocity of the issuing mixture is reduced.

Again thin spacers may be used to provide the ignition flame openings 11, the proportions being such as to cause considerable friction to the flow. Also the length of passage from the entrant side to the combustion side may be selected to apply the required reduction of the velocity. Such arrangements may be used separately, or in combination.

An incidental advantage of the use of a narrow ignition flame opening is that there is less likelihood of "lighting back," in fact, lighting back is virtually impossible under normal operating conditions with a very narrow opening.

With the use of a very narrow ignition flame opening 11, a burner such as described can be made very flexible in performance, as, with a high mixture pressure, a considerable amount of gas can be consumed per unit of length, the main flame being kept alight by the ignition flame or flames. Conversely, the rate of gas consumption can be made relatively low before the velocity of the mixture traversing the main slot 10 (or slots) is reduced sufficiently to cause risk of lighting back.

The invention is not limited to details of construction. Thus, the relative heights of the spacers and the strips may vary; e. g., the spacers may be sunk below the level of the strips, as shown.

The form of the serrations in the spacers may very to provide continuous or interrupted flames.

While I have described a burner which gives one central main flame and an ignition flame at each side, the arrangement may be such as to provide one main flame and one ignition flame, or two main flames placed one on each side of one ignition flame.

The relative widths and/or thicknesses of the strips and spacers may vary. For instance, for protection purposes we may bring the outer strips just beyond the ignition spacers at the entrant side.

The spacers may be continuous as shown, or may comprise a number of separate pieces at suitable intervals.

The outermost strips may be eliminated, their place being taken by the edges of the burner housing.

What is claimed is:

A gas burner including a longitudinally slotted tube, an assembly mounted in the slot in the tube and contacting the sides of the slot, said assembly comprising a plurality of plane parallel strip members and plane-sided serrated spacer members having outwardly pointed serrations interposed between and contacting neighbouring strip members for spacing said strip members apart, the points of the serrations being flush with the outer edges of neighbouring strip members, said strip and spacer members extending in parallel relation longitudinally of said tube with their plane sides in contact, these serrations extending below the parallel strip members, said strip members and said spacer members, collectively forming at least one main slot and at least one supplementary slot constituting passages for the flow of combustion mixture to the outlet defined by the upper edges of said strip and spacer members, the entrance to the main slot being substantially unobstructed by a spacer member having widely spaced serrations and interposed between two strip members, and the entrance to the supplementary slot being considerably obstructed by a spacer member having closely spaced serrations and interposed between two strip members.

ERNEST EDWARD TAVENER.
